ABSTRACT

An apparatus to facilitate the take-off on water skis including flotation gear to support the skier at the water level for starting and having a seat or positioner associated with ski guides to initially establish a proper position and attitude of the skier relative to the skis and the water's surface.

FLOATING PLATFORM FROM WHICH TO START WATER SKIING

CROSS-REFERENCE TO RELATED PATENT

This invention is an improvement on my previously known starter for use with water skis which is shown in my prior U.S. Pat. No. 3,179,222 issued Apr. 20, 1965. This known starter shows a ski slideway adapted to be fixedly mounted near the water surface, which can be made light weight and portable, but which nonetheless is adaptably supported on stationary legs while in use to position the stationary ski guides approximately at the level of the water.

This invention is also an improvement over my previously known starter shown in my prior U.S. Pat. No. 3,500,978 issued Mar. 17, 1970. In this case, the slide-way is provided with flotation, eliminating the need for support by stationary legs.

BACKGROUND AND SUMMARY OF THE INVENTION

The present invention relates to water ski starting devices like that shown in my aforementioned patents but is distinguished from these known devices in providing a sloped ski track for easier take-off, and a new construction design which provides both a stronger and a less expensive product, and which includes many additional features which add to its usefulness without adding to its cost. As fully explained in the above mentioned patents, a critical speed is required to produce the necessary hydro-dynamic lift on the skis and during the take-off or starting procedure the skier must accelerate from a stationary position to a speed equal to or faster than the critical speed. This invention makes it possible to accomplish the necessary acceleration from a dead start to hydro-dynamic support speed as smoothly as possible and minimizes jerking and straining in order to make the take-off easy and safe. It is also operative to minimize any disturbance to the skier's balance which might be expected to be felt upon the transition from the starter apparatus to the full water support of the skier.

It is, therefore, an object of this invention to provide an improved water ski starter device that makes the skier's take-off easy and safe.

It is another object of the invention to provide a water ski take-off guide means that can be used with a boat that is started from an idling speed.

It is another object of the invention to provide a floating water ski starter that is always positioned at the level of the water.

It is still a further object of this invention to provide a water ski starter apparatus having positioning means thereon to encourage the skier to assume the proper position relative to the skis and their planing position on the water such that surer and safer starts result.

These and other objects will appear more fully below in the more detailed description and drawings forming a part of the specification.

BRIEF DESCRIPTION OF THE DRAWINGS

FIG. 1 is a perspective view of the starter apparatus in use,

FIG. 2 is a top plan view of the starter apparatus,

FIG. 3 is a side elevation of the apparatus,

FIG. 4 is a bottom plan view of the apparatus,

FIG. 5 is an end elevation view of the rear part of the apparatus,

FIG. 6 is a cross-section view along the line VI—VI,

5 FIG. 7 is a cross-section view along the line VII—VII,

FIG. 8 is a cross-section view along line VIII—VIII,

FIG. 9 is a cross-section view along the line IX—IX,

10 FIG. 10 is a cross-section view along the line X—X,

FIG. 11 is a cross-section view along line XI—XI.

DESCRIPTION OF THE PREFERRED EMBODIMENTS

The starter apparatus for water skiers here shown is adapted to float in the water and thus ensures that the skier takes off exactly on the plane of the water's surface. For this purpose the preferred form of the apparatus includes a body 10 constructed of high density polyethylene and forming a hollow chamber for flotation of the apparatus. The body is relatively long, wide and flat thereby giving stability to the apparatus and smoothing out the effects of choppiness in the water or running waves. The flotation is of such magnitude that the body's floating characteristics are not greatly affected by the weight of the skier.

20 The hollow body 10 is constructed of an upper shell 11 and a lower shell 12. The shells contact, by nesting peripheral, concave, downwardly directed flanges 36 and 37 provided on each shell (see FIGS. 6 and 7). When secured with adhesive, this flange connection provides not only a strong, rigid air-tight seal, but also 25 a peripheral handle. The body is made even more strong and rigid by centrally located ribs (see FIGS. 6 and 7). These ribs are formed by contact of the open ended guide slots 21 and 22, which are formed longitudinally and concave, upwardly directed in the upper shell, and the skegs 13 and 14 formed in the lower shell 12. These ribs can be used to divide the body into air-tight compartments.

30 Further crush-resistance is provided by impressions 15 that rise from the lower shell to contact the upper shell.

The ski tracks 38 and 39 are formed of parallel impressions in the upper shell running longitudinally of the body. Each of the two ski tracks 38 and 39 consists of an open-ended guide slot 21 or 22, two horizontal floor elements 17 and 18 or 19 and 20, adjacent and parallel to the slot, and guide walls. The guide walls include a center guide wall 23 and inside guide walls 34 and 35.

35 The ski tracks are so impressed and related to the flotation center of the body, that although the front end of the track is at water level, the rear end is considerably above the water level. Thus, the track is sloped downwardly from rear to front. This slope not only helps in skier acceleration but also compensates for slight rear end dips that accompany the start of acceleration. To further smooth out the initial acceleration, rollers 25 are provided in aperture 24 at the take-up portion of the track.

40 The upper surface is also provided with holes 40 through the body for securing it in position, hand holds 41 for easy movement, and a non-skid surface 42 to avoid accidents on the wet surface.

The upper surface is also provided with a positioner 29 consisting of a seat 44 and legs 45 that position the seat over the tracks.

As best shown in FIG. 1, the flotation gear is designed to have good stability when a person is on the top side of the apparatus as it floats in the water. It is also arranged to float sufficiently deep in the water such that the water level floods the slots 21 and 22 and the floor elements 17, 18, 19 and 20 at the front end. This relationship is evident upon inspection of the left end of the representation included in FIG. 1.

In use, the skier mounts the apparatus, which can be held stationary by stakes as shown in FIG. 1, and takes his seat on positioner 29. The skis are set on rollers 25 to be positioned over the respective floor elements 17 and 18, and 19 and 20. The two skis are thus each loosely positioned to be moved between the inside walls 34 and 35 of flotation element 10 and the center guide wall 23. The skier inserts his feet in the harness on the skis and is ready for take-off.

With the apparatus here described, a boat may be gently moved into position and may even be allowed to drift into position to take up the slack in the tow rope. When all is in readiness the motor is gunned and take-off begins. As the skier is pulled forwardly he slides off the seat as the skis begin to move on rollers 25. The keels of the respective skis are guided by slots 21 and 22 and as the skier's body begins to move forwardly, there is a transfer of weight from the positioner to the skis when the buttocks leave the seat, which change in weight distribution nudges the skis forwardly and down the slope of the tracks. All of this action occurs rather instantaneously and automatically as forward motion is produced by the pull of the motorboat on the tow line, but the actions are guided by the relationship of positioner 29 and rollers 25 so that even an inexperienced skier is started forwardly without any jerk or other undue starting movement that might cause a loss of balance. Continued forward pull with an even rate of acceleration completes the take-off as the skis glide down the guide channels. The guide way of the starter apparatus has sufficient length so that by the time the skis reach the end of the floor elements 17, 18, 19 and 20, the speed is sufficient to produce the necessary hydrodynamic reaction to support the skier on the top of the water. Since the flotation gear always supports the end of the floor elements in position to be just at the level of the water, it is apparent that the skier is guided on his way at least in the beginning with a proper positioning of the knees, body and arms., and is delivered from the end of the starter apparatus with sufficient speed to continue his journey with a minimum liability of tumbling into the water and consequently being ducked at the beginning of a run as so frequently happens to the inexperienced skier. The positive control of ski action coupled with the smooth pull generated when a boat is started from an idling position, provides an ideal arrangement for starting the water skier on his journey.

A single ski may be used by a more experienced skier and if required at the start, a second balancing ski can be used in the other channel during take-off. It is obvious that this flotation ski start apparatus may be utilized at any location either in deep water or shallow. It may be allowed to drift or may be anchored. The apparatus is designed to have sufficient length and weight to be considered a permanent fixture to be left in the

water the same as an outboard boat and where tides or changing water level conditions are present, always floats at the water level to be ready at all times for immediate use.

5 The apparatus can easily be adapted for use with water sleds, but for all of the reasons apparent from reading the description above, it finds particular use for guiding water skiers on take-off.

10 The apparatus here disclosed is particularly useful for teaching beginners the art of water skiing. It is extremely difficult to master the balance required for an unassisted take-off from a position in the water and otherwise a sudden jerk type of pull must be mastered if a start is to be made from the shore line. The problems associated with such take-offs are very difficult for 15 beginners to contend with, as more fully set forth in my earlier patents mentioned above. As compared with the patented structures the improvement provided by this invention is of great value to the beginner because of 20 the assured smooth glide from the supported engagement of the skis on the apparatus to the fully water supported hydro-dynamic ride. With the new apparatus, the transition from the floating means to the hydrodynamic support is automatically controlled and is always perfect. In the older, prior device, manual adjustment to provide a fixed setting might not always provide for a smooth transition. Also, in water which may be somewhat wavy, only an average setting can be made, but with my new invention, even in waves, a 25 smooth transition takes place. This is particularly helpful in the case of beginners and adds a considerable degree of comfort to take-offs even for experienced skiers. In the present invention this smooth take-off is improved even further over the more recent prior device 30 by the slope of the track. The skier is actually being pulled down hill during the initial acceleration. Because the weight transfer brings natural downward and forward motion, the skier does not experience as great a shock of momentum transfer.

35 40 The flotation gear is preferably provided with a wide spread so that the apparatus will not tip over easily. As shown in the drawings, it is preferred that a rather flat tank be provided, laid flatwise in the water. Such disposition controls the depth to which the apparatus sinks 45 when skiers of different weights climb aboard and the difference between maximum and minimum submersion is kept within very close limits by such disposition of the tank.

50 The length of the guideway and float apparatus is not critical. It can be shortened when more powerful boats are used to accelerate the skier or a longer run can be provided if boats with a slower pick-up are to be used.

55 55 The description above covers the preferred form of my invention, but many modifications thereof may occur to those skilled in the art which will fall within the scope of the following claims.

What is claimed as new and desired to secure by Letters Patent is:

- 60 1. A water ski launcher comprising
 a. an elongated main body of substantial flotation throughout and formed of hollow plastic, and having broad upper and lower surfaces,
 b. two parallel tracks formed on the upper surface of the main body,
 c. a guide groove formed in each track, the depth of the groove being the same from one end of the

main body to the other, each track consisting of flat surfaces on either side of a groove and sloping with respect to said lower surface from the said one end to the other.

2. A water ski launcher, as recited in claim 1, wherein the surfaces of the tracks are provided with longitudinal grooves.

3. A water ski launcher as recited in claim 1, wherein the said upper surface of the main body is provided with non-skid areas.

4. A water ski launcher as recited in claim 1, wherein the main body is provided with an outwardly-extending horizontal strengthening flange lying midway between the said upper and lower surfaces and extending substantially entirely around its periphery.

5. A water ski launcher as recited in claim 4, wherein a seat is located over the said one end and furnished with legs that clamp to the said strengthening flange.

6. A water ski launcher as recited in claim 1, wherein the plastic is a high-density polyethylene.

7. A water ski launcher as recited in claim 4, wherein the main body is formed from two sheets of plastic, the sheets being drawn into oppositely-directed cavities and the edges of the dies containing the cavities pressing the periphery of the sheets together to form the said flange.

8. A water ski launcher as recited in claim 7, wherein the sheets are formed with inwardly-directed protuberances whose peaks are welded together and pierced to provide an anchoring bore through the main body.

9. A water ski launcher as recited in claim 1, wherein each of the surfaces has an upper face and a lower face, and the opposed lower face of the upper surface and the upper face of the lower surface are spaced a substantial distance from one another except that the groove forms a downwardly-directed protuberance in the upper surface which contacts the upper face of the lower surface.
